DESIGN FOR A SWIMMING SUIT OR THE LIKE

Margit Fellegi Laszlo, Los Angeles, Calif., assignor to Cole of California Inc., Los Angeles, Calif., a corporation of California

Application October 22, 1945, Serial No. 123,077

Term of patent 3½ years

(Cl. D3—17)

To all whom it may concern:

Be it known that I, Margit Fellegi Laszlo, a citizen of the United States of America, residing at Los Angeles, in the county of Los Angeles, and State of California, have invented a new, original, and ornamental Design for a Swimming Suit or the like, of which the following is a specification, reference being had to the accompanying drawing, forming a part thereof.

Fig. 1 is a front perspective view of a swimming suit showing my new design;

Fig. 2 is a side perspective view of the swimming suit shown in Fig. 1, and

Fig. 3 is a front view, on reduced scale, of the trunks portion of the design as it appears in open position.

The back of the swimming suit is conventionally plain.

I claim:

The ornamental design for a swimming suit or the like, as shown and described.

MARGIT FELLEGI LASZLO.
